UNITED STATES PATENT OFFICE.

MILDRED C. SCHMOLZE, OF NEW YORK, N. Y., ASSIGNOR TO FRANKLIN SIMON & CO.,
OF NEW YORK, N. Y., A CORPORATION OF NEW YORK.

DESIGN FOR A COAT.

Application filed January 9, 1925. Serial No. 11,977. Term of patent 3½ years.

To all whom it may concern:

Be it known that I, MILDRED C. SCHMOLZE, a citizen of the United States, and a resident of the city of New York, borough of Manhattan, in the county and State of New York, have invented a new, original, and ornamental Design for Coat, of which the following is a specification, reference being had to the accompanying drawing, forming part thereof, wherein the coat is distinguished by a quilted or embossed ornamental design below the pocket and at the rear, the rear or-

namentation extending to the sides and conforming in appearance to the ornamentation under the pocket, and a band of fur at the bottom of the coat.

Figure 1 is a view almost in side elevation, of a coat showing my new design.

Figure 2 is a rear view of the coat shown in Figure 1.

I claim:

The ornamental design for a coat, substantially as shown and described.

MILDRED C. SCHMOLZE.
